Attorney.

UNITED STATES PATENT OFFICE

WOLFGANG TURNWALD, OF SYRACUSE, NEW YORK

AUTOMOBILE HOOD CLAMP

Application filed December 7, 1927. Serial No. 238,266.

My invention relates to automobile hood clamps. The object is to provide an improved clamp which uses both spring force and spring reaction for holding down the hood, 5 and which also locates and holds the sidewise position of the hood walls independently of its normal support. The device causes tension on the spring in opposite directions upon the upward movement of the hood, thus 10 greatly increasing the holding force of the spring. This force is still further increased by properly proportioning the opposite ends of the lower catch with respect to its fulcrum; and the increased leverage thus secured upon 15 the lower lug or catch facilitates the engagement of the clamp with the upper lug or catch.

Automobile hoods usually are held down by means of four clamps and are supported by the radiator shell and car body. Lacing 20 is used in most cases to give the hood an elastic or resilient support and to prevent squeaks and rattles.

When driving over rough roads the hood is 25 in constant motion. Due to the flexibility of the car frame the radiator is displaced with respect to the body with a resultant sliding of the hood on its supports. Also the sides of the hood are subject to an up and down movement.

30 Most of the hood clamps, now in use, derive their holding force from a spring contained in the clamp; the reaction force of the spring being used to press the lower ends of the hood against their supports. While 35 threaded wing nuts have been used to engage the clamp, most clamps to-day are made to hook on, this latter method being more convenient. In order to make the hooking operation easy the spring force which can be used 40 is limited, and in most cases is insufficient to properly hold the hood down. The pressure exerted against the hood lace, particularly at the lower part of the sides, wears the lace out with the result of a ratty hood.

45 In order to overcome some of the above mentioned difficulties I have designed a hood clamp which uses both, spring force and spring reaction force for holding down purposes and which at the same time locates the 50 sides of the hood independently of its sup-

port. In this way wearing out of the hood lace should be eliminated entirely. Holding down the hood, aside from the doubled force, will further be facilitated due to the increased deflection of the spring, in case the hood 55 should move up slightly. As compared with the customary clamps, the spring in my clamp is deflected twice as much or more for the same movement of the hood, it therefore is equivalent to a spring twice as stiff. 60

55 My clamp comprises a double armed lever, one end of which engages the hood while the other end connects with the hook and spring assembly. By changing the ratio of the double armed lever with respect to its fulcrum, 65 the holding down force may be increased for a given spring force.

60 Referring to the drawings which illustrate merely by way of example a suitable embodiment of my invention:—

65 Fig. 1 is an elevation of my clamp showing adjacent parts in section, the open position being shown in broken lines.

70 Fig. 2 is a part plan part section on line 2, 2 of Fig. 1.

75 Fig. 3 is an elevation of a modification.

Fig. 4 is a part plan part section on line 4, 4 of Fig. 3.

80 Similar numerals refer to similar parts throughout the several views.

85 The side walls 7 of the hood are provided with the bifurcated hooks or lugs 8, for engagement with the usual engaging latching member 9. This latching member 9 is associated with the cylinder 10, housing the spring 11 which is effective between the upper end of rod 12 and the lower end of the cylinder. The lower end of rod 12 is provided 90 with the head 13 which cooperates with the outer end 14 of lever member 15, which is pivoted at 16 to the stationary lug 17. The inner end 18 of lever 14 is provided with the hook formation 19 for engaging or latching a pin or other suitable element 20 secured to 95 the lower part of the hood 7. All as shown in Figs. 1 and 2.

100 In Figs. 3 and 4 the construction is substantially the same except that the lever 15 is provided with a pin 21 adapted to engage

the hook 22 secured to the lower part of hood 7.

It will be noted that the extension 14 of the lever 15 is greater than the extension 18 from the pivot or fulcrum 16.

5 In operation; when the handle 23 of element 9 is lifted from the position shown in broken lines in Fig. 1, the end 18, having the hook 19 or pin 21, immediately engages locks 10 with the pin 20 or hook 22 and draws down the hood 7, which action is facilitated by the leverage secured by the position of the fulcrum of said lever 15. This greatly adds to the ease in engaging or latching the upper 15 element 9 with the bifurcated hook or lug 8.

It will also be noted that any upward movement of the hood, when the two catches are secured, will tend to pull down on the spring 11, which is already exerting a spring tension 20 on the element 9. Thus an increased spring tension is exerted to prevent upward movement of the hood.

It will also be noted that the engagement 25 of the hook and pin means of the lower clamp or catch element secures the position of the lower margin of the hood wall away from and independent of any supporting means, thus preventing wear of the lacing and also preventing rattling of the hood against the 30 usual supporting walls.

What I claim is:—

1. In a device of the character described, 35 the combination of upper and lower fixed latching elements and cooperating upper and lower movable latching elements, and means for exerting spring tension between said movable latching elements, the parts so arranged that the lower cooperating fixed and movable elements will come into latching engagement 40 prior to the engagement of the upper fixed and movable latching elements.

2. In a device of the character described, 45 the combination of upper and lower fixed latching formations and cooperating upper and lower movable latching elements, means for exerting spring tension between said movable elements, and means for magnifying the power exerted by the spring upon the latching 50 action of the lower element.

55 3. In a device of the character described, the combination of upper and lower fixed latching elements and cooperating upper and lower movable latching elements, the lower movable element adapted to exert a downwardly directed force upon the hood before the engagement of the upper elements, and means for magnifying the said force exerted by said lower movable element relatively to the initial force applied.

60 4. In a device of the character described, 65 the combination of upper and lower fixed latching elements, cooperating upper and lower movable latching elements, the lower movable element comprising a pivoted lever, one end of which is adapted to engage the

lower fixed element, the other end resiliently connected to the upper movable element.

5. In a device of the character described, 70 the combination of upper and lower fixed latching elements, cooperating upper and lower movable latching elements, the lower movable element comprising a pivoted lever, one end of which is adapted to engage the lower fixed element, the other end resiliently connected to the upper movable element, said 75 lever having its fulcrum nearer the end engaging the lower fixed element.
